PAGE HOLDING DEVICE FOR BOOKS

John D. Gray, Valley City, N. Dak.

Application June 4, 1934, Serial No. 728,872

10 Claims. (Cl. 281—42)

My invention relates to page holders for books and particularly to movable page holders.

An object of my invention is to provide a page holder for books whereby the pages of an opened book may be securely held so as to maintain a desired page in exposed position.

Another object is to provide such a page holder including a page holding element which is movable toward the top and bottom of a page held thereby so as to successively expose all portions of the page and so as to function as a marker for marking any desired line of indicia on the page.

A further object is to provide such a page holder which is of simple, light, compact, rugged and inexpensive construction, which presents a neat appearance and which may be easily and quickly placed in operative position or moved toward the top or bottom of a page held thereby.

These and other objects and advantages of the invention will be more fully set forth in the following description made in connection with the accompanying drawing, in which like reference characters refer to similar parts throughout the several views, and in which:

Fig. 1 is a partially broken away top view of an open book having my page holding device operatively attached to one of the covers thereof;

Fig. 2 is a section taken along the line 2—2 of Fig. 1 as indicated by the arrows, and

Fig. 3 is a partial view looking toward the free edge of the cover of the book.

Referring to the drawing, a book to which my device is shown attached includes covers C, a back section B and pages P.

A guide 4 is formed of a relatively long strip of sheet material having its longitudinal edge portions turned to form inwardly directed flanges 4a disposed parallel to and spaced from the central portion of the strip. The mutually facing edges of the respective flanges are arranged in spaced parallel relation to each other.

At each end of the guide 4 an attachment ear 4b is formed for attachment of the guide to the cover C of a book. The guide 4 is applied to the outer side of one of the covers C of a book parallel to and closely adjacent the free outer edge of the cover. The guide 4 is attached to the cover C in the position described by means of rivets 4c or other fastening means securing the attachment ears 4b to the cover. The ears 4b are twisted slightly so as to space the one of the flanges 4a nearest the edge of the cover C a slight distance from the cover C as best shown in Fig. 2.

55 A flat rectangular element 5 is placed in the

guide 4 so as to be held in the position described by the flanges 4a and the unturned or back portion of the guide 4 to serve as a slider. The slider 5 is of such width as to extend transversely of the guide 4 substantially from one side to the other thereof. Obviously the slider 5 is free for rectilinear movement longitudinally of the guide 4 and is limited by the guide 4 to such movement.

A page engaging element or finger 6, formed of spring metal or other suitable resilient material, is rigidly secured at one of its ends to the medial portion of the slider 5 on the side of the slider facing the space between the edges of the respective flanges 4a of the guide 4. The finger 6 extends from its point of attachment to the slider 5 through the space between the respective flanges 4a, through the space between the edge of the cover C and the flange 4a closest adjacent thereto, around the edge of the cover C and above and transversely of the inner side of the cover C toward the portion thereof adjoining the back section B of the book. The finger 6 is of such length that it terminates in a free end disposed above and slightly outwardly of the portion of the cover C immediately adjoining the back section B of the book. The finger 6 is tensioned to press toward the inner side of the cover C.

In normal use of the device any desired number of the pages P of a book to which the device is attached may be disposed between the finger 6 and the cover C. The finger 6, being tensioned to press toward the cover C, will cooperate with the cover C to grip any of the pages P disposed between the finger 6 and the cover C.

The finger 6 may obviously be easily raised to place additional pages P thereunder or to remove pages P from thereunder.

Since the finger 6 is mounted on a slider 5 which is movable longitudinally of the guide 4 it may be moved toward the top or bottom of a page P held thereby to expose to view any desired portion of the page.

The finger 6 may be used to advantage as a marker to identify or mark any line of printing or other indicia on the page P thereunder to which the user wishes to direct his attention. The finger 6 may of course be moved to various positions so as to successively mark various lines in any desired order and in any of its positions it is disposed parallel to the lines.

The finger 6 is rigidly connected to the slider 5 as has been described and is preferably disposed at right angles to the direction of movement of the slider 5 so as to interfere with view

of a minimum number of lines of printing or other indicia.

A pair of my devices may be used with a single book if desired, each one being attached to one of the respective covers of the book in the manner previously described.

It is to be noted that the arrangement of my device is very neat and compact and that the slider 5 and the open side of the guide 4 are concealed from view.

10 It is apparent that I have invented a novel, simple, compact and effective form of holder for pages of a book whereby the pages of an open book may be held, wherein the page engaging element is movable to successively expose to view 15 all portions of a page held thereby, which conceals a very small portion of a page and which may be effectively used to mark lines of indicia on a page.

20 It will, of course, be understood that various changes may be made in the form, details, proportions and arrangement of the parts, without departing from the scope of my invention, which generally stated, consists in a device capable of 25 carrying out the objects above set forth and in the novel parts and combinations of parts disclosed and defined in the appended claims.

What is claimed is:—

1. A page holding device for books comprising 30 guide means extending along the side edge portion of one of the covers of a book, an element guided by said guide means for movement longitudinally thereof and restrained by said guide means against other movement and a resilient 35 page engaging element rigidly mounted at one of its portions on said first mentioned element and extending in another of its portions over the inner side of said cover, said page engaging element being tensioned to bear toward said cover 40 to grip between itself and said cover any pages of said book disposed therebetween.

2. A page holding device for books comprising 45 guide means extending along the side edge portion of a book, an element limited by said guide means to movement longitudinally thereof and a resilient page engaging finger rigidly mounted at one of its ends on said first mentioned element and extending therefrom over the inner side of said cover, said finger being tensioned to 50 press toward said cover to grip between itself and said cover any pages of said book disposed therebetween.

3. The structure defined in claim 2 and said 55 finger being disposed at right angles to the direction of movement of said first mentioned element.

4. A page holding device for books comprising 60 guide means extending adjacent and parallel to the side edge of one of the covers of a book and secured to the outer side of said cover, an element 65 guided by said means for movement longitudinally thereof and restrained thereby against other movement and a page engaging element carried by said guided element and extending around the edge of said cover and inwardly across the inner side of said cover to confine between itself and said cover pages of said book disposed therebetween.

5. The structure defined in claim 4 and said page engaging element being constructed of resilient material and tensioned to press toward said cover to cooperate with said cover to grip said confined pages.

6. A page holding device for books comprising, 10 an element located at the side edge portion of one of the covers of a book and slidably longitudinally thereof, guide means limiting movement of said element to rectilinear movement 15 and a finger formed of resilient material and rigidly secured at one of its ends to said element, said finger extending from said element over and transversely of the inner side of said cover and being tensioned to bear theretoward whereby 20 said finger will cooperate with said cover to grip pages of said book disposed between said finger and said cover.

7. A page holding device for books comprising 25 an element associated with one of the covers of a book adjacent the outer edge thereof, means for guiding said element for sliding movement toward the upper and lower edges of said cover and a page engaging finger mounted on said element and extending across the inner side of said 30 cover toward the back section of said book, said finger being formed of resilient material and being tensioned to press toward said cover so as to cooperate with said cover to grip any pages of said book disposed between said finger and said cover.

8. A page holding device for books comprising 35 a guide extending along the side edge portion of one of the covers of a book, an element retained in said guide for longitudinal sliding movement relative thereto, a finger formed of resilient material secured to said element and extending therefrom over and transversely of the inner side of said cover, said finger being tensioned to bear 40 toward said cover to grip between itself and said cover any pages of said book disposed therebetween.

9. A page holding device for books comprising 45 a guide extending along the outer side of the side edge portion of one of the covers of a book, an element retained in said guide for longitudinal rectilinear movement therein, a finger rigidly secured at one of its ends to said element and extending therefrom around the side edge of said cover and over and transversely of the inner side 50 of said cover, said finger being constructed of resilient material and being tensioned to bear toward said cover whereby said finger will cooperate with said cover to grip pages of said book disposed between said finger and said cover.

10. A page holding device for books comprising 55 guide means extending along the side edge portion of a cover of a book, an element guided by said guide means for movement longitudinally thereof and a page engaging finger, mounted 60 at one of its ends on said element, extending therefrom over the inner side of said cover and arranged to press toward said cover whereby any pages of said book disposed between said finger and said cover will be gripped therebetween.

JOHN D. GRAY.
